UNITED STATES PATENT OFFICE.

CLINTON T. COATES, OF ST. LOUIS, MISSOURI, ASSIGNOR OF ONE-THIRD TO ALBERT W. ALBRECHT AND ONE-THIRD TO CHARLES A. CLOUD, BOTH OF ST. LOUIS, MISSOURI.

METAL-BALL-ROLLING MACHINE.

Application filed March 24, 1921. Serial No. 455,059.

To all whom it may concern:

Be it known that I, CLINTON T. COATES, a citizen of the United States, residing at St. Louis, Missouri, have invented a new and useful Metal-Ball-Rolling Machine, of which the following is a specification.

This invention relates to metal ball rolling machines, and consists in the novel construction hereinafter disclosed.

10 An object of the invention is to provide a machine whereby metal balls may be rolled from polygonal slugs or pieces of metal which will be absolutely accurate in spherical dimensions and which will have a uniform density throughout.

Another object of the invention is to provide a machine of the class described including a plurality of rollers and forming-dies arranged adjacent thereto with convenient 20 means for adjusting the dies.

Another object of the invention is to provide a machine of the class described including a plurality of rollers arranged in connection with forming-dies, whereby a continuous forming-passage will be provided so that balls may be formed from polygonal slugs or pieces of metal fed into the passage at one end and discharged at the other end thereof.

30 Numerous additional structural advantages will be apparent from the following detailed description taken in connection with the accompanying drawings, in which

Fig. 1 is an end elevation of the machine 35 partially in section illustrating the invention.

Fig. 2 is a side elevation.

Fig. 3 is a vertical section through the machine illustrating the operative parts.

40 Fig. 4 is a view of the several forming-dies shown partially in section and arranged in the position in which they are mounted in the machine.

Fig. 5 is a cross section of a fragment of 45 the machine designed particularly to illustrate the shape of the passage between the rollers and dies.

In the embodiment of the invention illustrated in the drawing the frame of the machine is made up of side members 1 arranged to be attached to the permanent support of the machine by bolts 2. A plurality of rollers 3, 4 and 5 are mounted on shafts

6, 7 and 8 respectively, said shafts extending transversely of the machine and being 55 arranged one above the other and journaled in bearings 9, 10 and 11 respectively formed in the side members of the frame. The roller 3 is provided with a groove 12, the surface of which is roughened or knurled so 60 that it will be an abrasive surface for operating upon the material out of which the balls are formed. The roller 4 is likewise formed with a groove 13 the surface of which is preferably smooth. The roller 5 65 is composed of two sections split in the center with one section fast on the shaft 8 and the other section loose or floating thereon. This roller has a groove 14 the surface of which is preferably smooth. 70

The forming-dies 15, 16 and 17 are mounted transversely in the machine and are supported by horizontal ledges or walls 18, 19 and 20 respectively, so arranged that the dies will be on alternate sides of the rollers. 75 The dies have segmental faces in which grooves complementary to the grooves of the rollers are cut, said grooves being indicated by 21, 22 and 23 respectively. In order to properly adjust the dies lugs 24, 25 and 26 80 are formed on the frame of the machine over the dies, and set screws 27 are threaded through the lugs and bear against the upper face of the dies.

Rods 28 extend transversely of the machine in such position as to pass through elongated slots 29 formed in the dies. The rods 28 are held in place in the side members of the frame by nuts 30. The radial adjustment of the dies in respect of the rollers is accomplished by means of a pair of matching wedge-shaped plates 34 for each die, said plates being positioned back of the dies. Said plates 34 are supported in slots 31, 32, and 33 in the side members 1. Thus 95 it will be observed that an accurate adjustment of the dies in respect of the rollers may be accomplished and that, after the adjustment has been effected, the dies will be held in place by the screws 27. 100

The rollers are driven from a power shaft 35 supported in a standard 36, a power pulley 37 being provided on the shaft 35 for the application of power thereto. The shaft 35 carries a pinion 38 that meshes with a 105 gear 39 carried by a counter-shaft 40. The

counter-shaft 40 has a pinion 41 meshing with the upper one of a train of gears including the gears 42, 43 and 44 mounted respectively on the ends of the shafts 6, 7 and 8. 5 This power transmission mechanism drives the shafts 6, 7 and 8 and thereby the rollers that are fast thereon alternately in reverse directions.

It will be noted by reference to Fig. 5, particularly, that the cavity made up by the matching faces of the channels in the rollers and in the dies is oblong in cross section, that is to say the lateral walls of the cavity are slightly extended from a true circle. It will 10 also be noted that the upper wall of the channel or groove 21 of the die 15 is deflected upwardly from the circle upon which the channel is formed, so as to provide a greater space between the die and the roller for the 15 admission of the slugs from which the balls are rolled; and, also, that the wall of the channel in the die 17 is deflected downwardly from the circle upon which the channel in 20 said die is formed, so as to provide a discharge for the balls after they are formed.

A machine made up as above described provides a continuous passage for the material, the slug or cube of material from which the ball is to be formed entering the cavity 30 between the upper end of the channel of the die 15 and continuing through the passage, being discharged from the machine at the lower end of the channel in the die 17. The abrasive surface of the channel 21 tends to 35 crush the polygonal-shaped slug of metal entering the machine to conform to the vertical diameter of the cavity formed by the roller and die. This cavity is of a diameter slightly greater than the finished diameter 40 of the ball. The cavity between the rollers and dies gradually diminishes in vertical diameter until it is adjusted to the exact size of the finished ball. When the material passes between the die 16 and the central 45 roller it has been formed to the diameter required and is then passed into the cavity between the lower die and roller. As explained above this lower roller is split so that one section of it is fast on the shaft and the other 50 section is a floating section. This arrangement provides for a rotary movement being imparted to the ball as it continues through the cavity, thereby polishing or finishing the ball. At the end of the cavity the ball is 55 deflected from the machine.

From the foregoing it will be understood that the machine provides means for accurately forming balls of required dimensions which, when completed, will have a surface 60 that is perfectly smooth, and that the balls will be of uniform density throughout.

I am aware that the invention may be modified in certain particulars without departing from the spirit and scope thereof.

65 I do not limit myself, therefore, to the exact

construction and arrangement shown, but what I claim and desire to secure by Letters Patent, is:—

1. A machine for rolling metal balls, comprising side frames, a plurality of grooved rollers supported for rotation between the side frames, horizontal ledges in connection with the inner sides of the side frames, forming dies mounted on said ledges for cooperation with said rollers respectively and having grooves matching the grooves in the rollers, a plurality of wedges supported by said side frames for adjusting each of said forming dies upon said ledges in any desired relation to the rollers, and elements for holding the forming dies down upon the ledges. 75

15 2. A machine for rolling metal balls, comprising side frames, a plurality of grooved rollers supported for rotation between the side frames, horizontal ledges in connection with the inner sides of the side frames, forming dies mounted on said ledges for cooperation with said rollers respectively and having grooves matching the grooves in the rollers, a plurality of wedges supported by the 80 side frames for adjusting each of said forming dies upon said ledges in any desired relation to the rollers, and releasable means supported by the side frames for holding said forming dies upon said ledges. 90

20 3. A machine of the character described, comprising side frames, grooved rollers journaled for rotation between said side frames, ledges in connection with said side frames, forming dies adjustable upon said ledges relative to the rollers respectively and having grooves matching the grooves in the rollers, wedges for holding said forming dies from 100 outward movement, and means for holding said forming dies down upon said ledges. 105

25 4. In a machine of the character described, a pair of side frames, grooved rollers journaled for rotation one above the other between said side frames, ledges extending from the inner sides of said side frames, 110 forming dies mounted on said ledges for cooperation with said rollers respectively and having grooves in their inner faces matching the grooves in the rollers, elements supported by the side frames for holding said forming dies from movement away from the rollers, and elements supported by the side frames for preventing said forming dies from rising from said ledges. 115

30 5. In a machine of the character described, the combination of a pair of spaced side frames, a pair of rollers supported one above the other between the side frames and having grooves in their peripheries, a forming die cooperating with each of said rollers, a third roller formed of two relatively movable parts forming a circumferential groove, a forming die cooperating with said third roller, and mechanism for rotating said pair of rollers and one part of said third roller. 120

130

6. In a machine of the character described, a shaft, a roller on said shaft composed of two sections one of which is rigid with the shaft and the other of which is loose on the 5 shaft, and said two sections having a circumferential groove between them, a forming die supported adjacent to said roller and having a groove in its inner face matching the groove in the roller, and means for rotating said roller.

7. In a machine of the character described, the combination of a pair of side frames, a roller supported between said side frames and having a circumferential groove, a die 15 having a segmental face adjacent to said roller and having a groove in the segmental face thereof matching the groove in the roller, an additional roller supported below the first one composed of two relatively movable parts having a circumferential groove 20 between them, a forming die cooperating with said additional roller, and mechanism

for rotating the first-named roller and one part of the additional roller.

8. In a machine of the class described, the 25 combination of a frame, a roller transversely supported in the upper part of the frame and having a groove therein the surface of which is roughened, a die having a segmental face disposed adjacent to one side of the 30 roller, there being a groove in said face deflected downwardly on gradually decreasing radii, a second roller arranged in the frame below said first-named roller and having a 35 smooth surfaced groove therein a die arranged in the frame adjacent to said roller and on the opposite side from said first-named die, a third roller mounted below said second named roller, said last named roller being split, and means for driving said two 40 first-named rollers, and a section of said last-named roller.

CLINTON T. COATES.
